UNITED STATES PATENT OFFICE.

RUDOLPH HILLNER, OF SCHENECTADY, NEW YORK, ASSIGNOR TO GENERAL ELECTRIC COMPANY, A CORPORATION OF NEW YORK.

TURBINE BUCKET-WHEEL.

1,156,529.

Specification of Letters Patent. Patented Oct. 12, 1915.

Application filed June 10, 1914. Serial No. 844,197.

To all whom it may concern:

Be it known that I, RUDOLPH HILLNER, a citizen of the United States, residing at Schenectady, county of Schenectady, State of New York, have invented certain new and useful Improvements in Turbine Bucket-Wheels, of which the following is a specification.

The present invention relates to rotors for elastic fluid turbines, and particularly to the formation of the bucket bases and the assembling of the same in the wheel.

At the present time it is the common practice to provide the rotor with an undercut slot in the rim into which the bucket bases are introduced through suitable openings in the side or face of the rim, these openings being afterward closed by means of locking pieces or notch blocks. The number of these openings varies with the diameter of the wheel, from two to eight being usually found necessary.

According to the present invention I avoid the use of side or face openings for the introduction of the buckets by forming the bucket bases in such a manner that they may be inserted edgewise into the slot and then turned into engaging position.

For a consideration of what I believe to be novel and my invention attention is directed to the accompanying specification and the claims appended thereto.

Referring to the drawing wherein I have illustrated one form which my invention may take, Figure 1 is a side view partly in section of a portion of a turbine rotor; Fig. 2 is a plan view; and Fig. 3 is a perspective showing one bucket in place in the undercut slot and a spacing piece and second bucket adjacent thereto.

4 indicates the periphery of the web member of a turbine rotor having formed therein the undercut groove or slot 5, the upper edges of which are beveled as indicated at 6. The upper faces 6^a of the groove are slightly tapered in an upward direction from the side wall of the groove to its edges.

7 indicates the bucket proper and 8 the base thereof. This base in horizontal section is a parallelogram with its longer sides of greater length than the width of the slot. The thickness of the base is less than the narrowest width of the slot. Formed in the sides of the base are the two notches 9, the faces of which extend at substantially the

same angle as do the end faces of the base proper. This angle will depend upon the length of the base as compared to the width of the slot and will be such that when the base is turned into final position the end faces will take against the sides of the slot. The faces 9^a of the bucket bases are slightly tapered to cooperate with the tapered faces 6^a. As will be obvious in order to insert the bucket bases into the slots the same are introduced longitudinally and then turned. This brings the tapered surfaces 6^a and 9^a into contact with a wedging action and any torque on the buckets in this same direction tends to tighten the same. This wedging action insures that the bucket bottom is firmly seated on the bottom of the slot and that the bucket base is rigidly fastened in a radial direction.

10 indicates a spacing piece which is formed in the same manner as are the bucket bases.

By avoiding the use of side slots for the introduction of the buckets I am enabled to increase the efficiency of the rotor since in place of the locking pieces there will be buckets. According to this invention but one locking piece will be required. This may take any suitable form and will be located between the first and last buckets to be inserted as will be obvious.

A turbine rotor constructed according to this invention has the further advantage that it may be more quickly and easily assembled, and much more readily repaired as no special tools are required. This is of particular advantage in case it is required to reblade the machine after being installed.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is,—

1. The combination with a turbine rotor having an undercut slot with tapered upper surfaces upon each side of the mouth of the slot, of a bucket having notches in its base with tapered surfaces to take against the tapered surfaces of the slot, said base being

parallelogrammatic in section with its longer sides of greater length than the greatest width of the slot, and its shorter sides substantially parallel to the side walls of the slot, and of less thickness than the narrowest width of the slot.

2. A turbine rotor comprising a web member having an undercut slot in its periphery with tapered upper surfaces upon each side of the mouth of the slot, a plurality of buckets mounted therein each having a base of less thickness than the narrowest width of the slot and parallelogrammatic in section with its longer sides of greater length than the maximum width of

the slot, and its shorter sides substantially parallel to the side wall of the slot, said base being provided with tapered surfaces which coöperate with the upper tapered surfaces of the under-cut slot for wedging 20 the bucket base against the bottom of the slot, and spacing pieces between the respective buckets having substantially the same formation as the base of said buckets.

In witness whereof I have hereunto set 25 my hand this 9th day of June, 1914.

RUDOLPH HILLNER.
